UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 22,061, dated December 20, 1892.

Application filed November 22, 1892. Serial No. 452,876. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons and other Similar Articles, of which the following is a specification, reference being had to the accompanying drawing, forming a part thereof.

The figure is an upper or front face view of a spoon handle embodying my design.

The leading features of my design are as follows. The shank portion *a* is represented as a woody twig. At the point where the handle begins to widen there is a cluster of three leaves *b*, one of them laid down toward the

shank and the other two extended outwardly. Joining onto these leaves is a full blown apple blossom *c*, and just above it are two other smaller apple blossoms *d d'*, and extending beyond these is a number of buds *e* not yet blown. The outer edges of the leaves, blossoms, and buds impart their irregular outline to the margin of the handle.

25

What I claim is,

The design for the handles of spoons and other similar articles as herein shown and described.

AUSTIN F. JACKSON.
